CONNECTING MEANS FOR FLOOR RACKS

Filed April 18, 1927

UNITED STATES PATENT OFFICE

MALCOLM S. JOHNSON, OF CHICAGO, ILLINOIS, ASSIGNOR TO E. PAYSON SMITH, OF SPRINGFIELD, ILLINOIS

CONNECTING MEANS FOR FLOOR RACKS

Application filed April 18, 1927. Serial No. 184,486.

My invention relates to means for hingedly connecting together the floor racks or superposed floor sections employed in railroad freight cars for the shipment of commodities requiring proper ventilation or air circulation intermediate of the main car floor and the racks and therefore beneath the commodities.

These superposed floors or racks are usually made in suitable sections arranged lengthwise of the car on each side of the longitudinal center of the car, to permit the same to be easily handled and also enable them to be independently raised and lowered out of and into operative position when desired.

My invention has for its object the provision of a simple device whereby the predetermined sections will be hingedly secured together so as to permit the respective floor-rack sections to be moved into parallel juxtaposition, either into face-to-face or back-to-back relation, depending upon whether certain of said sections are to remain in lowered position or are in raised position against the car wall.

The objects and advantages of my invention will be apparent from the following detailed description of the preferred embodiment of the invention shown in the drawing 30 wherein—

Figure 1 is a sectional plan of a portion of a car, the floor whereof is provided with floor-rack sections connected together by my improved connecting means, with certain sections folded over into face-to-face relation, while other sections are folded into back-to-back relation and raised against the car side wall.

Figure 2 is a top plan view of portions of adjacent floor-rack sections connected together by my improved means.

Figure 3 is a side elevation of the connecting means and portions of floor-rack sections as shown in Figure 2.

Figure 4 is a sectional view taken substantially on the line 4—4 of Figure 3, viewed in the direction of the arrows.

Figure 5 is a side elevation of adjacent ends 50 of floor-rack sections connected together by

my improved means and shown in back-to-back relation.

The invention is not limited to any particular type of freight car, as the general features of the invention may be used in any refrigerator-car or in any ordinary freight car employing a supplemental floor or floor-racks superposed on the car-floor proper, wherein certain of the sections of the floor-rack are usually permanently hinged to the floor proper adjacent to the side wall of the car so as to permit the rack to be folded up parallel with the car side wall when the car is used for ordinary lading or when the car floor is to be cleaned. Freight-cars, when employed for the shipment of bananas for instance, must be provided with suitable floor-racks in order to not only provide suitable air circulation, but also to permit the bananas, usually shipped in large clusters, to be packed with the butt-ends of the stems of each cluster resting on the floor-racks. In shipping bananas in this manner it is essential that the openings between the runners or planks be not greater than a certain predetermined dimension (generally specified by the railroads), in order that the stems will not enter between these adjacent planks and allow the heavy clusters to rest on the bananas, which would result in damaging the same. It is, therefore, likewise essential, when the floor-rack is down in position, to keep the spacing between the respective sections of the floor-rack within the prescribed dimensions. My improved connecting means between the respective sections is devised to meet the requirements referred to while at the same time permitting easy manipulation of the comparatively heavy sections and allow compact folding thereof when required, without lateral play or shifting of a section relative to its adjacent section.

As my invention pertains to the means for hingedly connecting the respective floor-rack sections to each other, a detailed description of the car proper need not be entered into.

The floor-racks are generally made in sections of suitable length to extend intermediate of the car-door openings and the ends of the freight holding portion of the car,

with separate sections at the door openings, and of width substantially equal to half the width of the car interior, in order that similar sections may be arranged on each side of the longitudinal center line of the car.

In the drawing, Figure 1, a portion of the side walls of a car are shown at 10, 10 provided with the usual side-door openings 11, 11; the doors being omitted. The floor of the car is shown provided with the floor-racks consisting of suitable sections 12, arranged lengthwise of the car on each side of the door-opening 11, and door sections 13.

It is usual, for convenience in handling, to make the floor-rack sections in pairs for each door opening, namely a pair of similar floor-rack sections 13 being arranged on each side of the longitudinal center line of the car; said sections being adapted when in lowered position to completely cover the portion of the car floor proper intermediate of the opposite door openings. The door-opening sections, as disclosed in the drawing, are pivotally secured so that one section will fold onto the floor-rack on one side of the door-opening while the other section will fold onto the floor-rack on the opposite side of the door-opening.

The floor-racks consist of suitable sleepers or stringers 14 of length equal to the desired length of the respective floor-rack sections and of suitable number in parallel spaced relation as shown in Figure 1. The sleepers or stringers are in turn provided with superposed runners or planks 15 arranged in predetermined spaced parallel relation with each other transversely of the sleepers or stringers to which they are secured. As previously stated, the spacing between the superposed runners or planks must not exceed a predetermined specified dimension for reasons heretofore set forth. The floor-rack sections 12, namely the sections intermediate of the door-openings and the ends of the lading holding portion of the car are usually hingedly connected by means of a well known type of hinge (not shown) to the floor proper or to the side wall of the car so as to permit the floor-rack to swing upwardly against the side wall of the car, as indicated at the lower right hand side of Figure 1.

In order to secure all of the sections against displacement and loss, it is essential that the door-opening sections 13 be hingedly secured in place to the respective adjacent sections 12 in a manner which will permit ready movement of the door-sections into and out of operative position without requiring special or undue manipulation in such swinging movement. As is well known in railroad practice, freight cars are generally "spotted" in order to permit loading of a freight car at a distance removed from the loading platform; this operation being carried out by means of hand-trucks wheeled through the door-openings of

the freight cars intermediate of the loading platform and the particular car to be loaded; suitable planks being laid from car to car to permit such operation.

It is apparent that during such loading operations, the floor-rack sections at the door-openings, must be removed not only to provide a suitable trackway for the hand-trucks, but also to prevent injury to the floor-rack sections. During this operation, if the main floor-rack sections of a car through which the truck is to pass are down in operative position, it is then customary to swing the door-opening sections 13 over onto the main floor-rack sections, namely in the face-to-face relation shown in Figure 1 at the upper side of the figure so as to provide a clear opening. Where the main or permanently hinged sections, for illustration the sections 12, are folded up out of operative position into parallel relation with the car side wall, the door sections of the floor-rack, or adjacently hinged sections, should then be capable of folding into back-to-back relation as illustrated in the lower side of Figure 1 and as shown in Figure 5. In order to permit the latter condition it is necessary to arrange the sleepers or stringers 16 of the door sections 13 in staggered relation with the stringers 14 of the permanently secured or hinged sections 12 in order to permit the respective stringers of the one section to fold intermediate of those of the other as shown in Figure 5 and thus allow the respective sections to be arranged substantially parallel with each other and in vertical position adjacent to the car side wall as shown in Figure 1.

My improved connecting means preferably consists of a pair of suitable metal plates 17 preferably to be secured to the longitudinal sides and adjacent to the ends of stringers 14 as shown in Figures 2 and 3 in any suitable manner, as for example by bolts 18 disposed through the stringers 14 and held in place by suitable nuts 19; the bolts being also preferably provided with suitable washers as at 20. The bolts 18 preferably are of the type having a flat head 21 adapted to come flush with the outer face of the plate 17 as shown in Figure 4, so as not to interfere with proper movement of the connecting member 22. One end of member 22 is pivotally secured by means of a suitable rivet as at 23 to the plate 17 attached to stringer 14, see Figure 4. The adjacent end of stringer 16 of the floor-rack section 13, is likewise provided with a similar plate 17 secured to the longitudinal face of the stringer as previously described, and this plate has the opposite end of the connecting member 22 pivotally secured thereto at 23, see Figures 2, 3 and 5. As shown in Figure 2 the plates 17 are secured to the opposite sides or longitudinal faces of the stringers 14 and 16 in order that

the non-flexing connecting element 23 may extend parallel with the stringers.

The connecting member 22 preferably consists of a somewhat U-shape metal strap with the pivot-forming rivets 23 disposed through the ends of the member which are secured to the plates 17 at a point just beneath the runners or planks 15. These connecting members 22 are of such length that the spacing between the connected floor-rack sections will be equivalent to or not greater than the predetermined designated spacing between the superposed planks 15 of a section, as will be seen in Figures 1, 2 and 3. At the same time the ends of the connecting member 22 are a distance apart approximating the vertical width of either sleepers or stringers 14 or 16 in order to permit the stringers of two pivotally connected sections to be moved into parallel nesting relation as shown in Figure 5—and at the lower side of Figure 1 to the right of the door opening 11,—thus permitting the connected rack-sections to be disposed parallel with each other in the back-to-back compact relation disclosed. When the sections are folded into back-to-back relation, the connecting member 22 will be disposed in a horizontal plane; whereas when a section is folded over onto an adjacent section in face-to-face relation the connecting member 22 will be vertically disposed as shown in dotted lines in Figure 3, at which time the connecting member will straddle the end planks 15 of the two connected sections.

It is apparent from the construction shown that no lateral or sidewise play of the connected sections is possible and that the pivotal connection between the sections is such that a free swinging movement into either of the positions mentioned may be quickly made without special adjustment or movement other than the lifting of a section upwardly and onto the lowered floor-rack section for face-to-face relation, or swinging the free end through the arc of a horizontally disposed circle after the large permanently secured section has been swung upwardly against the side of the car wall. With my improved connecting means a binding of the connecting means is impossible, while at the same time a positive spaced relation between the adjacent ends of the connected floor-rack sections is at all times maintained when the floor-rack sections are in operative position.

The structure disclosed is believed to be the simplest embodiment of the invention which has been described in terms merely as terms of description and not as terms of limitation, as structural modifications are possible without, however, departing from the spirit of my invention.

What I claim is:

1. Connecting means for the floor-rack sections of a railroad car comprising, in com-

bination with a pair of aligned sections, a single piece member, the opposite ends whereof are pivotally connected to the opposing ends of said floor-rack sections, while the intermediate portion of said member is disposed toward one side of the pivotal axes of said ends.

2. Connecting means for the floor-rack sections of a railroad car comprising, in combination with a pair of aligned sections, a connecting member having a non-flexing intermediate portion and two end portions disposed toward the same side of the longitudinal axis of the intermediate portion, and means whereby said end portions are pivotally connected to the adjacent ends of two rack sections.

3. Connecting means for the floor-rack sections of a railroad car comprising a non-flexing single piece member the ends whereof are disposed beyond one longitudinal side of the member, said ends being of equal length, and means pivotally connected to said ends whereby the connecting member may be connected to the adjacent ends of two floor-rack sections.

4. In combination with the floor-rack sections of a railroad car, the stringers of adjacent sections being arranged in longitudinal staggered relation, pivot providing members secured to the opposite faces of the stringers of adjacent sections, and a non-flexing single piece member having ends disposed toward one side of the body portion of said member, the ends of said member being pivotally secured to said first mentioned members.

5. Connecting means for the floor-rack sections of a railroad car comprising a pair of attaching plates, and a non-flexing U-shape strap, each end whereof is pivotally connected to one of said plates.

6. Connecting means for the floor-rack sections of a railroad car comprising a single piece member composed of two attaching portions of equal length and a rigid connecting portion integral with said attaching portions and disposed at an angle thereto.
